COMBINED DISPLAY AND CHARGING UNIT FOR A BATTERY OPERATED TOOTHBRUSH

Meyric K. Rogers, La Grange Park, Ill., assignor to Sunbeam Corporation, Chicago, Ill., a corporation of Illinois

Filed Jan. 20, 1967, Ser. No. 5,509

Term of patent 14 years

(Cl. D4—16)

FIG. 1.

FIG. 2.

Fig. 3.

Fig. 5.

FIG. 1 is a front perspective view of a combined display and charging unit for a battery operated toothbrush showing my new design;

FIG. 2 is a side elevational view thereof;

FIG. 3 is a top plan view thereof;

FIG. 4 is a rear elevational view thereof;

FIG. 5 is a top plan view similar to FIG. 3 but with the transparent cover removed; and

FIG. 6 is an enlarged fragmentary sectional view taken on line 6-6 of FIG. 4.

The characteristic features of my design reside in the base as shown. The broken line showing of the toothbrush power handle and brushes in FIG. 1 are for the purposes of illustration only.

I claim:

The ornamental design for a combined display and charging unit for a battery operated toothbrush, as shown and described.
